Attn: Mrs.

UNITED STATES PATENT OFFICE.

JOSEPH G. HUYE, OF NEW ORLEANS, LOUISIANA.

BOX.

Application filed March 27, 1924. Serial No. 702,362.

This invention relates to knock-down set-up boxes more particularly intended for hat boxes for use by retail milliners, though also being well adapted to use in the jewelry trade and for use in shipping goods, said boxes being of heavy paper board or card board and, of course, varying in weight in accordance with the purpose to which it is to be put in use, and the present invention 10 has more particularly in view the means for locking sections of such a box together in assembled relation and means for maintaining said locking or interengaging means in operative position.

15 Boxes of this type have given excellent results, but the added material, labor and wastage involved in affixing or providing a locking flange on the body member has involved considerable expense in the total, 20 considered on a quantity production basis. Also, a rather heavy and expensive weight of material or paper board has heretofore had to be used to be sure of the sides of the body and the lip of the bottom section remaining stiff in spread position in order that 25 the locking means on said body and said lip will remain in interlocking engagement. Also, it has been found that it is not feasible with prior known constructions having a 30 continuous lip to fold the lips of said bottom sections flat to conserve space in shipping and storing and have them operate to the desired efficiency as thereafter assembled; and, further, it has been found that in order 35 that said lips may be folded appreciably to save space and still function to a passable extent as thereafter assembled it is necessary to fold the entire lip inward toward the inner face of the bottom section, which fold- 40 ing operation requires considerable care and time, and therefore expense, and results in a rather clumsy folded construction that does not make a solid stack or bundle and gives an awkward appearance to the individual 45 bottom sections.

The objects of the present invention are to provide a box of the above type of a particular construction in which the locking flange or element or tongues on the body element, may be stamped out from the body member in the same stamping operation by which the blank for said body member or

section is formed, so being integral therewith and avoiding all expense for labor and material in especially subsequently providing it; to provide a construction which will particularly lend itself to a very light material without sacrifice of security of engagement of the interengaging or locking means; and to provide a construction wherein the 55 lips of the bottom section may be folded flat within a minimum time and with minimum effort and care and will lie flat and make a slick solid compact stack or bundle for shipment and storage while increasing the security of the interlock and permitting the use 60 of light weight inexpensive material without sacrificing any degree of security or ease of assemblage, all of which objects, among others, are accomplished by the construction, combination and arrangement of parts 65 all as hereinafter more particularly set forth, described and claimed.

In the accompanying drawings representing but two embodiments of my invention 70 merely by way of illustration of the practice thereof:

Figure 1 represents a perspective view of a box embodying my invention and broken away at several points to aid in giving a 80 better understanding of the details thereof;

Figure 2, a top plan view of one side portion of the box with the cover or top section removed;

Figure 3, a view at right angles to Fig. 2; 85

Figure 4, a sectional perspective view on a greatly enlarged scale of the body and bottom sections superposed just before assembly, said view being taken approximately on a line corresponding to line 5-5 of 90 Fig. 3;

Figure 5, a sectional perspective view on a greatly enlarged scale on line 5-5 of Fig. 3;

Figure 6, a perspective detail fragmentary 95 view of one lower corner of a body embodying my invention in a slightly modified form;

Figure 7, a top plan fragmentary view of one corner of a box, with the cover removed, 100 according to Fig. 6; and

Figure 8, a sectional fragmentary view on the line 8-8 of Fig. 7.

Referring now in detail to the drawings,

A designates the cover or top section of the box, B the body section or "ring" and C the bottom section having an edge flange or lip D provided with a preferably continuous 5 interior locking flange E having an abrupt edge face presented downwardly toward the upper face of said bottom section.

The body section B has integral depending flanges F having their end edges mitered, 10 said flanges, in the assembled box, lying against the upper face of the bottom section substantially at right angles to the sides of said body portion with their end edges in, or substantially in, engagement to act as a 15 bracing and spreading device to hold the lower part of the body section spread and prevent its deformation to maintain the locking tongues 1 in such position that their ends will be in locking engagement with the 20 lower abrupt edge face of the corresponding locking flange E.

The locking tongues 1 are formed by making inverted approximately U-shaped 25 cuts in the lower part of the body portion or section B, severing the material thereof on three sides and leaving the tongues integral with the body section along a line coincident, as shown, or substantially coincident, with the line along which the respective 30 spreading flanges F fold inward, so that the inward folding of the latter will cause the outward protrusion of said tongues 1, the material of which they are formed and their combination with the respective spreading flanges F resulting in 35 said tongues 1 each being slightly yieldingly resilient and being yieldingly resiliently held or positioned as a whole, so that when the bottom C is applied its lip D and flange E in engaging with the respective 40 outer faces of the lower part of the body section B will engage the lower outer faces of said locking tongues or small locking flanges 1 and cause them to yieldingly resiliently fold back toward the adjacent face of 45 the respective outer faces of the body section B and at least partially back into the openings from which they are respectively cut until the lower face or abrupt edge of 50 the locking flange E passes upward far enough to release said tongues 1, which will then spring outward due to their resiliency, until their outer faces are in engagement with the inner face of the lip D and their 55 upper edge or end faces are directly beneath and in, or substantially in, contact with the lower abrupt edge face of said locking flange E.

As thus described the body section may 60 be used with a heavy material stiff bottom section C regardless of the lip corner construction.

However, in order that light cheap material may be used for the body section B and 65 for the bottom section C and lip D and that

said sections may be folded in the easiest and most economical manner to the most compact flat state for shipment and storage and still as assembled make a very tight fit with each other without any appreciable 70 separation or bulge apart between corners, I form the body section B with slots, preferably arcuate as shown, near each corner, all of said slots being of the same size and form, in the same horizontal plane, and 75 preferably equidistant from their respective corners, as shown. These slots may, of course, be made during the stamping out of the body section blank.

To cooperate with said slots I form the 80 lip D with a very appreciable extension 2 at each corner, said extensions being illustrated as substantially equal in height to the height of the lip D between said extension and as being integral therewith and being continuous and extending on both sides of the corners respectively and each itself having sharp upper distant corners 3, said corners 3 of each extension 2 projecting through the 85 respective slots adjacent the respective corners of the body member B and lying against the inner face of the adjacent portions of the respective sides of said body section B and bulging said material of said sides slightly outward at said points, so putting the body section B and the end section C under opposed tensions, resulting in holding the lip D in snug engagement at all 90 points with the lower part of body section B and so insuring a snug fit and positive locking engagement between the tongues 1 and the flange E at all times.

Further, by providing the corner extensions 2 I provide greater space for pasting or otherwise suitably connecting the elements of the lip together at the corners of the section C, thus securing greater strength for a given size and weight of lip E and also, because of such extensions 2 I obtain added strength to the box as assembled at 100 the points where it is most liable to be knocked and put to the greatest test in use.

In the modification illustrated in Figures 6, 7 and 8 I have substituted two independent tongues 2^a at each corner for the corner extension, these tongues extending through horizontal slots in the adjacent sides of the body section B'. Otherwise the construction and operation are the same as in the preferred form, only the opposition of the tension of the one section to that of the other is far less pronounced and the advantages of greater strength at the corners and greater space for pasting are not present.

Having thus described my invention, what I claim as new and desire to secure by Letters Patent is:

1. A receptacle comprising two paper-board sections, one of said sections being 130

- provided with integral spreading flanges and with integral resilient tongues extending from said flanges and protruding beyond the lateral outer faces of said section, 5 and the other of said sections being formed to snugly partially receive the former section and having a locking flange adapted to ride over said resilient tongues until it passes beyond said tongues, said tongues being adapted to spring out when free from said flange in order that their edges may lie in the path of travel of said locking flange in the reverse direction to prevent the separation of said sections.
- 15 2. A receptacle comprising two paper-board sections, one of said sections being provided with spring tongues and the other of said sections being formed to snugly partially receive said former section and having a locking flange adapted to ride over said tongues until it passes beyond them, said tongues being adapted to spring out when free from said flange in order that their edges may lie in the path of travel, in the reverse direction, of said flange, and said sections being formed to have interlocking bracing engagement with each other in a horizontal plane beyond said locking flange to set up opposed tensions throughout all portions of each of said sections lying in and adjacent to said plane, whereby to maintain said flange and said tongues in operative relation.
- 35 3. A receptacle comprising two paper-board sections, one of said sections being provided with spring tongues and the other of said sections being formed to snugly partially receive said former section and having a locking flange adapted to ride over said tongues until it passes beyond them, said tongues being adapted to spring out when free from said flange in order that their edges will lie in the path of travel, in the reverse direction, of said flange, and said sections being angular in cross section and being formed to have interlocking bracing engagement with each other at the respective corners in a horizontal plane beyond said locking flange to set up opposed tensions throughout all portions of each of said sections lying in and adjacent to said plane to hold the opposed faces of said flange and the first mentioned section in snug engagement to maintain said locking tongues and flange in operative relation.
- 55 4. A receptacle comprising a continuous deformable permanently tubular form body section and a bottom section having a continuous lip, said sections being of paper-board, in combination with interengaging means carried by said body section and said lip on all sides of said receptacle, said sections being angular in cross-section, and said body section being formed with two slots adjacent to, and equi-distant from, its re-
- spective corners, and the lip of said bottom section being provided with vertical extensions at its respective corner portions respectively received in said slots to thereby oppose the spring action of the bottom section to the spring action of the body section, whereby said lip and said body section will be maintained taut and in snug engagement throughout the length of their opposed faces in order to maintain said interengaging means at all points in operative position.
5. A receptacle comprising a body section and a bottom section, both sections being of paper material, in combination with interengaging means carried by said sections, said sections being angular in cross-section, said body section being formed with two arcuate opposed slots adjacent to, and equidistant from and on different sides of, its respective corners and in the same horizontal plane, and said bottom section having a continuous lip provided with vertical extensions, each said extension being located at, and extending equidistant on each side of, a corner and having their distant upper corner portions received in and extending through the respective cooperating slots in said body section and engaging against the inner face of the adjacent portions of said body section to set up opposing tensions in said body section and said bottom section to hold said interengaging means in operative relation.
6. A receptacle separate deformable continuous open ended body section for a knock-down set up paper box, said body section being provided at one end with a spreading and bracing flange and having a plurality of duplicate locking tongues integral with said flange and in the operative position of said flange protruding beyond the lateral face of said body section and adapted to yield to permit the application of an element to said body section and adapted to snap outwardly when released by such element to assume operative locking position.
7. A receptacle separate deformable continuous open ended body section for a knock-down set-up paper box, said body section being provided at one end with integral foldable spreading and bracing flanges and having a plurality of duplicate locking tongues integral with said body section and in the operative position of said flanges protruding beyond the lateral outer faces of said body section and adapted to yield to permit the application of a snug-fitting encircling element to said body section and adapted to snap outwardly when released by said element to assume operative locking position.
8. A receptacle separate paper bottom section having a body portion, a continuous lip extending entirely about its edge and pro-

vided on its inner face with an element adapted to be engaged by a third element, said section being angular in cross-section and having its lip provided at each corner with a continuous extension away from said body portion providing a greater area in a given size lip for usual connection, said ex-

tension being adapted to cooperate with a third element to maintain said lip in correct angular shape.

In testimony whereof, I have signed my name to this specification at New Orleans, Louisiana, this 25th day of March, 1924.

JOSEPH G. HUYE.
